(57) **CLAIM**

I claim the ornamental design for a sanitizable security sleeve, as shown and described.

DESCRIPTION

FIG. 1 is a top right perspective view of the sanitizable security sleeve, assembled, mounted on a wall and enclosing an electronic device;

FIG. 2 is a bottom left perspective view of the sanitizable security sleeve, assembled, enclosing an electronic device; FIG. 3 is top view of the assembled sanitizable security sleeve, enclosing an electronic device and mounted on a wall;

FIG. 4 is a bottom view of the assembled sanitizable security sleeve;

FIG. 5 a right side view of the of assembled sanitizable security sleeve, enclosing an electronic device and mounted on a wall;

FIG. 6 a left side view of the assembled sanitizable security sleeve, enclosing an electronic device;

FIG. 7 is a front view of the assembled sanitizable security sleeve, enclosing an electronic device and mounted on a wall;

FIG. 8 is a rear view of the assembled sanitizable security sleeve, enclosing an electronic device; and,

FIG. 9 is a top right perspective view of the sleeve and holder portions of the sanitizable security sleeve, shown separately prior to assembly, with holder portion mounted to a wall.

The broken lines shown in the figures are directed to environment and form no part of the claimed design.

1 Claim, 9 Drawing Sheets
